US00D476959S

(12) **United States Design Patent** (10) Patent No.: **US D476,959 S**
(45) Date of Patent: ** Jul. 8, 2003

(54) **SEMICONDUCTOR DEVICE**

(75) Inventors: **Junji Yamada**, Tokyo (JP); **Seiji Saiki**, Fukuoka (JP)

(73) Assignee: **Mitsubishi Denki Kabushiki Kaisha**, Tokyo (JP)

(**) Term: **14 Years**

(21) Appl. No.: **29/164,710**

(22) Filed: **Jul. 31, 2002**

(51) LOC (7) Cl. **13-03**

(52) U.S. Cl. **D13/182**

(58) Field of Search **D13/110, 123, D13/125, 179, 182; 174/16.3, 52.1, 52.2, 52.4, 261; 211/4.17, 162; 361/718, 728, 747, 748, 760, 774, 784, 785, 813, 820**

(57) **CLAIM**

The ornamental design for a semiconductor device, as shown and described.

DESCRIPTION

FIG. 1 is a front, top and right side perspective view of a semiconductor device, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.
